UNITED STATES PATENT OFFICE.

WILLIAM M. DUNCAN, OF ALTON, ILLINOIS.

BOILER-FURNACE.

1,179,084.

Specification of Letters Patent. Patented Apr. 11, 1916.

Application filed December 12, 1913. Serial No. 806,343.

To all whom it may concern:

Be it known that I, WILLIAM M. DUNCAN, a citizen of the United States, residing at Alton, in the county of Madison and 5 State of Illinois, have invented certain new and useful Improvements in Boiler-Furnaces, of which the following is a specification.

The present invention relates to certain 10 improvements in furnaces for boilers, and has to do with the form and arrangement of the furnace, as well as the mode or manner of its construction.

The features of invention herein disclosed 15 are intended particularly for use in connection with water tube boilers. However, it will presently appear that they are in no wise restricted to such use, and that although I have illustrated them as used in 20 conjunction with a water tube boiler, still they may be used with equal facility and advantage in connection with other classes of boilers.

In previous constructions of furnace it 25 has been customary to provide for the gradual expansion and burning of the gases from the time they are formed adjacent the front end of the furnace until they finally pass upward into contact with the boiler tubes or flues. In such a construction the gases do not fully ignite and burn in the furnace. Furthermore, in such a construction it is customary to slant or slope the furnace roof upward away from the grate and 30 toward the rear so that such roof does not lie parallel to the surface of the grate or fuel bed at all points. This is a disadvantage for the reason that the radiation of heat from the furnace roof takes place at 35 right angles to the surface of such roof, and therefore cannot be at right angles to or directly down on to the bed of fuel.

One of the objects of the present invention is to so construct or form the roof of 45 the chamber wherein the combustion occurs that said roof shall lie parallel to the grate so that the heat radiation from the roof will be straight down on to the fuel bed at all points. This will insure the production of 50 a much higher temperature in the combustion chamber than can otherwise be obtained, with a correspondingly better fuel consumption and efficiency. At the same time such construction of the furnace roof 55 will enable the provision of a combustion chamber having substantially uniform cross

section throughout its length so that the gases will expand to their full extent as soon as they enter such chamber and will thereafter remain in expanded condition. 60

Another object of the invention is to so construct the forward portion of the furnace as to provide what may be termed an ignition arch, that is a portion of the roof structure beneath which igniting of the fuel 65 will commence, and wherein the distillation of the lighter volatile matters will occur. This arrangement taken in conjunction with the arrangement in which the gases are immediately fully expanded in the combustion 70 chamber, and in which the heat radiation from and to the fuel bed is direct or at right angles, will insure a thorough consumption of all of the products of distillation before they reach a point where the 75 temperature is sufficiently low to allow condensation of unconsumed carbon. In this way a construction is produced which will burn the fuel with a total absence of smoke, or at any rate with a minimum production 80 of smoke for any given quality of fuel.

Another object of the present invention is to so construct or arrange the aforementioned features that they may be conveniently used in conjunction with a grate of 85 the traveling chain style, various forms of which are in familiar and constant use.

Other features of the invention relate 90 particularly to the manner of constructing the furnace and particularly the roof portion thereof. It is a familiar fact that the rear portion of the furnace roof generally burns away most rapidly, and therefore one of the features of my invention is to provide 95 a construction such that this portion of the roof can be conveniently reconstructed without interfering with the balance of the roof structure.

Other features and objects will appear 100 from a detailed description of the invention, which consists in the features of construction and combination of parts herein-after described and claimed.

In the drawings: Figure 1 shows a vertical longitudinal section through a furnace 105 structure embodying features of my invention showing a portion of a water tube boiler mounted above the same, and showing in outline a familiar type of chain grate stoker in place; Fig. 2 is a view similar to 110 that of Fig. 1 with the exception that it is on a larger scale and shows portions of the

roof blocks in section to better illustrate the manner of constructing the roof; and Fig. 3 shows a vertical cross section taken on the line 3—3 of Fig. 1 looking in the direction of the arrows, Fig. 3 being on an enlarged scale and the stoker being removed.

In the several figures the boiler is designated 4 and the stoker 5. The boiler is supported in the customary manner. Beneath the central portion of the boiler is a wall 6 having the substantially vertical lower front face 7 and the slanting upper face 8. A deflector or partition 9 directs the gases up and around the forward portions of the water tubes. The grate illustrated is a familiar construction of stoker chain grate having the grate portion 10 which travels from the front to rear and carries the fuel bed. The hopper 11 contains the fuel in the first instance, a vertically slideable door 12 controlled by the chains 13 serving to regulate the height of the opening 14 through which the fuel is carried into the furnace by the chain. On the height of this opening depends to a large extent the thickness of the fuel bed. This construction is familiar and well known.

Above the forward portion of the chain grate is mounted or supported the roof 15 of a combustion chamber 16. This roof extends rearwardly to the point 17 somewhat in advance of the wall 6, so as to provide the passage 18 through which the gases gain access to a space 19 before they come into contact with the boiler. In previous constructions of furnace with which I am familiar, it has been customary to allow the expansion of the gases to take place gradually as they approach the chamber 19, but in the present case I have provided the combustion chamber 16 in which the gases expand at once to full volume, and in which they burn.

As illustrated particularly in Figs. 1 and 2, the roof 15 is substantially parallel to the grate, so that the aforementioned direct radiation of heat to and from the fuel bed is obtained at all points throughout the length of the fuel bed. Inasmuch as the roof of the combustion chamber is parallel to the fuel bed throughout its entire length, it necessarily follows that the gases will immediately expand to the full amount, and will remain in such expanded condition during their entire travel throughout the entire length of the combustion chamber. For this reason they will immediately become and remain in a state where complete combustion of the volatile matter may be most easily and completely carried on. This fact taken in conjunction with the unusually high temperature obtained in the combustion chamber by the direct back and forth radiation will insure a very thorough and

complete consumption of all of the volatile matter.

Of course the fuel must be initially heated when it enters the furnace so that the distillation of gases will commence as soon as the fuel bed enters the combustion chamber and so that ignition will commence as soon as possible. For this purpose I have provided what may be termed an ignition arch. It will be noted that the forward end of the combustion chamber is closed by means of a partition or wall 20. This wall extends down to a point somewhat above the maximum desired opening of the gate 12, so that its lower surface in effect provides an ignition arch 21 over the forward end of the fuel bed. This arch is of sufficiently high temperature to insure ignition of the fuel before the same enters the combustion chamber, and also serves to thoroughly commence the distillation of the volatile contents of the fuel at that time.

From the foregoing it will be seen that the arrangement herein disclosed is such that as rapidly as the fuel enters the furnace it is ignited, and is such that as fast as the gases are formed they expand to their full volume in the combustion chamber.

I will now describe more in detail the construction of the roof of the combustion chamber. It was previously stated that the rear portion 17 of this roof tends to burn away most rapidly, for the reason that the gases pass around the same in their travel from the combustion chamber to the boiler. Other portions of the roof are, of course, subjected to such heat and conditions that they will in time burn away and therefore it is desirable to be able to repair or renew all portions of the roof from time to time as that may be necessary. The construction herein disclosed is such that the roof of the combustion chamber can be readily built up, perfectly supported when once constructed, and such that replacements and repairs, particularly of the rear end 17, can be most easily effected. A number of transversely extending supporting members 22 extend across the furnace structure above the combustion chamber. As a simple and rigid form of construction, I have illustrated each of these members as composed of a pair of channels 23 placed back to back and having their ends embedded in or supported by the side walls 24 and 25 of the furnace structure.

The roof proper comprises a plurality of blocks 26 of suitable form, and of fire resisting material, said blocks being preferably arranged in rows from front to rear as is well illustrated in Fig. 3. Extending through the upper portions of the blocks of each row is a hollow rod 27 on which the blocks of that row are suspended or hung. Each of the rods 27 may be supported from each crosswise extending member 22 by a

plate or bar 28, and as a simple means of effecting this suspension, each plate extends downwardly a sufficient distance to allow the rod to be passed through a hole in its lower end. The plates in turn are preferably set in between the pairs of channels, and are supported on such channels by means of pins or the like 29. Those blocks 30 of the rear portion of the roof which are particularly subjected to burning are so supported that they can be readily removed from the rear ends of the rods without the necessity of disturbing the remainder of the roof construction. For this purpose each rod extends rearwardly some distance from the most rearward crosswise extending member 22, as best illustrated in Fig. 2. In order to effectively support the rear portion of each of the rods 27 the plate 28 supported by the rearmost member 22 supports a short rod or bar 31, from which in turn the plates 32 depend to support the rod 27.

It will be seen that as the rear blocks 30 burn away the rear end of the corresponding rod 27 may also be burned, or at any rate subjected to such a heat as to reduce or destroy its carrying or supporting power. For this reason I prefer to terminate each rod 27 somewhat forwardly of the most rearward block 30 and to insert a plug or the like 33 into the end of the rod, said plug in turn serving to support the rearmost blocks. By means of this construction the plugs can be renewed from time to time as the rearmost blocks 30 are renewed without the necessity of disturbing any other portion of the roof structure.

The customary form of sheet metal enclosure 34 may be built up over the roof structure if desired, for the purpose of giving a finished appearance to the furnace. It will be seen that the furnace roof extends some distance to the rearward of the front end of the boiler. By carrying the roof rearward in this manner the front and rear inclosures or walls of the space 19 may be made to diverge from each other as best illustrated in Fig. 1, so that the volume or cross sectional area of said space increases in size as it proceeds upwardly. As a simple means of effecting this construction a crosswise extending member 35 may be provided for supporting the front wall 36, a crosswise extending member 37 serving to support the slanting portion 38 of the front wall.

If desired, a sight hole 39 may be provided for inspecting the operation of the forward portion of the combustion chamber, a sight hole 40 for inspecting the operation of the ignition arch, and a sight hole 41 for inspecting the operation of that portion of the furnace wherein the gases pass up-

ward into the space 19. An opening 42 serves to give access to the rear portion of the furnace either for construction or repair. 65

From the foregoing it will be seen that I have herein disclosed a furnace arrangement and construction such that as fast as the gases form they immediately expand 70 into a chamber of considerable size and volume, and which chamber is of substantially uniform size or cross-section throughout its length from front to rear. It will also be seen that I have associated with such 75 chamber another portion wherein the fuel is originally ignited and wherein the distillation of the volatile matters commences. It will also be seen that there is a peculiar relationship or combination between the 80 combustion chamber and the grate for the reason that at the same time that I provide a combustion chamber of uniform size or cross-section I obtain a construction in which the roof of the combustion chamber 85 is parallel to the grate or fuel bed at all points so as to give the aforementioned advantages of direct right angled radiation.

I do not limit myself to the particular arrangements and construction herein illustrated and described, except as I may do in the claim, but I include within the scope of my invention any equivalent arrangements or constructions operating or capable of operating in equivalent manners to produce 95 equivalent results.

I claim:

In a boiler furnace, the combination with the grate, of a rear wall extending upwardly adjacent to the rear end of the 100 grate, the upper portion of the front face of said wall slanting rearwardly up to the boiler, a combustion chamber over the forward portion of the grate, said chamber having a substantially flat roof extending 105 rearwardly to a point close to the rear wall, another wall extending upwardly from the roof of the combustion chamber and sloping forwardly into contact with the front end of the boiler, and a wall closing the upper 110 portion of the front end of the combustion chamber, the roof of the combustion chamber lying substantially parallel with the grate, whereby there is provided over the front portion of the grate a combustion 115 chamber of substantially uniform cross section communicating in its rear portion with an expansion chamber of larger horizontal section in its upper portion than in its lower portion, substantially as described.

W. M. DUNCAN.
